UNITED STATES PATENT OFFICE.

STEPHEN KARSZ, OF DETROIT, MICHIGAN.

SASH HOLDER.

Application filed March 25, 1927. Serial No. 178,320.

This invention relates to improvements in sash holders, and refers more particularly to a device, which, though it may be employed for holding two sashes against vertical movement when they are both in closed position, is primarily intended to prevent either sash being moved when one or both of them are open.

It is an object of the invention to provide a sash holder for holding the sashes against vertical movement when either or both of them have been opened to the desired extent, so that a window may be safely left slightly open with the assurance that a burglar cannot open it further from the outside when the locking device is set, and thereby obtain entrance to the premises.

Another object of the invention is to provide a sash holder which may be cheaply manufactured and quickly secured on the upper portion of the lower sash after the latter is in position in the window frame, and to equip the device with a locking member which may be easily turned into locked or unlocked position.

A further object of the invention is to provide a sash holder, which, when in locked position, bears gently against the upper sash until an attempt is made to move either sash, in which case the locking member exerts lateral pressure against the side of the upper sash and renders it practically impossible to move either sash.

Having thus broadly outlined the purposes of the invention, I will now describe an embodiment thereof with the aid of the accompanying drawing, in which:

Figure 1 illustrates a sectional elevation of an upper and a lower window sash, with the sash holder in unlocked position on the latter.

Figure 2 shows a similar view with the sash holder in locked position.

Figure 3 is a plan view of Figure 2, and Figure 4 is an enlarged section on the line 4-4 of Figure 3.

Referring to the drawings, 1 designates an upper sash and 2 a lower sash of ordinary construction. On the latter a plate 3 is fastened as by screws 4. The sides of the plate, which usually consists of a stamping, are turned upwards and inwards to form guides 5 to receive the sides of a slide 6. On the ends of the latter adjacent to the upper sash forwardly extending arms 7 are provided. These arms have openings 8

therethrough to support the ends 9^a of an eccentric roller 9. It will be noted that the arms should be so spaced that they may pass freely between the guides 5, to permit easy insertion of the slide 6 after the guide plate has been secured in position on the upper sash.

Through the slide an irregular opening 10 is provided, and 11 indicates a lever pivotally mounted therein on the plate 3. The lever is pivotally supported by a screw 12 which passes through a hole 13 in the plate and takes into the upper sash 2. The front portion 10^a of the opening 10 is so shaped that the operating end 14 of the lever 11 forces the slide forward as the lever handle 15 is moved from free position 15^a indicated in Figure 3 to engaging position 15^b. The back portion 10^b of the opening 10 should be so shaped as to clear the heel 11^a of the lever in all positions of the lever and slide.

It will be noted that the slide 6 with its arms 7, and the lever 11, may be readily stamped out as well as the plate 3, and the roller 9 and its ends 9^a cheaply produced so that the device may be manufactured at a minimum cost. Moreover the whole of the device may be quickly and cheaply installed. Firstly by securing the plate 3 on the sash; secondly, by sliding the slide 6 into position on the plate; and thirdly, by placing the lever 11 in the opening 10 in the slide and inserting the screw 12 through the hole 13 in the plate and screwing it into the sash.

Obviously the device may be made so that the lever handle 15 turns to the right in order to unlock it instead of to the left as shown in the drawing; and, when desired, two sash holders may be employed one on each side of the upper portion of the lower sash, though ordinarily it is found that one is sufficient.

While in the foregoing the preferred embodiment of the invention has been described and shown, it is understood that the construction is susceptible to such modifications as fall within the scope of the appended claims.

What I claim is:

1. In a sash holder, the combination of a plate, a slide adapted to move back and forth thereon, said plate having a hole therethrough, said guide having an irregular opening therethrough, a lever partly seated on said plate in the irregular slide opening, a fastening means taking into said hole by

which the lever is pivotally secured, an operating end on said lever adapted to be turned against the side of said irregular opening to force said slide forward, said operating end 5 extending forwardly substantially in line with the movement of said slide when the latter is in forward position, and an engaging member on the front end of said slide adapted to engage a sash.

10 2. In a sash holder, the combination of a plate having guides on its sides, a slide adapted to move back and forth in said guides, said slide having an irregular open-

ing therethrough, a lever partly seated in said opening and pivotally mounted on said plate, an operating end on said lever 15 adapted to be turned against the side of said irregular opening to force said slide forward, said operating end extending forward substantially in line with the movement of said slide when the latter has been moved 20 into forward position, and an eccentric roller revolvably mounted on the front of said slide adapted to bear against a sash.

STEPHEN KARSZ.
